UNITED STATES PATENT OFFICE.

PAMELA P. MCCLINTOCK, OF TITUSVILLE, PENNSYLVANIA.

DESIGN FOR A SPADE OR SHOVEL.

SPECIFICATION forming part of Design No. 32,854, dated June 19, 1900.

Application filed May 18, 1900. Serial No. 17,174. Term of patent 14 years.

To all whom it may concern:

Be it known that I, PAMELA P. MCCLINTOCK, a citizen of the United States, residing at Titusville, in the county of Crawford and State of Pennsylvania, have invented a new and original Design for Spades or Shovels, of which the following is a specification.

My invention relates to a design for spades or shovels, which is illustrated in the accompanying drawings, in which—

Figure 1 is a front elevation of a spade or shovel embodying my design. Fig. 2 is a cross central sectional view. Fig. 3 is a central longitudinal sectional view.

My design consists of the stem *a*, with the laterally-extending shoulders *b*, the lower corners of the blade being cut away, as shown

at *c*, the lower edge having also the upwardly-projecting centrally-disposed recess *d* and the blade having at its center a longitudinal and transverse curve *e*.

Having thus described my invention, what I claim, and desire to secure by Letters Patent, is—

The design for a spade or shovel substantially as herein shown and described.

In testimony whereof I have hereunto set my hand in the presence of two subscribing witnesses.

PAMELA P. MCCLINTOCK.
